UNITED STATES PATENT OFFICE

ROBERT B. PEALER, OF WARREN, OHIO, ASSIGNOR TO THE BORDEN COMPANY, OF WARREN, OHIO, A CORPORATION OF OHIO

DIESTOCK

Application filed September 10, 1930. Serial No. 480,929.

This invention relates to a die stock of that type, wherein chasers are fixedly mounted in a suitable barrel which has a sleeve adapted to enter an actuating frame. The actuating frame preferably carries a pawl which engages ratchet teeth for rotation with the sleeve. Preferably the ratchet teeth are on a ring which is permanently but rotatably mounted in the handle frame carrying the 10 pawl, the ring having a key-way connection with the driven sleeve.

Tools of the above character have been manufactured and marketed by my assignee for many years, there being provided a series 15 of barrels with heads and chasers of different dimensions for different sizes of pipes but with identical sleeves, so that all of the barrels cooperate with the same actuating frame.

It is the object of my invention to provide a 20 tool of the character described which has all of the advantages of the tool marketed by my assignee, and which has the further advantage of providing a more satisfactory chip clearance and means whereby the chaser teeth 25 may be readily oiled in their most active region as they continue to act on the pipe.

My invention, though of specific character, does remedy a disadvantage of many years standing in the die stocks of the type referred 30 to as heretofore marketed. This invention is illustrated in the drawing and is herein-after described in detail.

In the drawings Fig. 1 is a face view of a die stock embodying my invention; Fig. 2 35 is a face view omitting the chaser-holding ring, the actuating frame being partly in section to show the action of the pawl and ratchet ring; Fig. 3 is an edge view with the actuating frame in section; Fig. 4 is a section of the 40 barrel through the chasers parallel with Figs. 1 and 2, and looking away from the actuating frame; Fig. 5 is a detail in cross section on a chordal plane, indicated by the line 5-5 on Fig. 4.

As shown in the drawing, 10 indicates the 45 barrel or driven chaser-carrier for my die stock, with which the present invention is concerned. This barrel has a sleeve-like portion 11 coaxing with the driving mechanism as 50 hereinafter explained. Beyond this sleeve-

like portion is an annular outwardly extending flat ring-like portion 12 which carries on its outer face chaser housings each formed by the parallel spaced walls of longitudinal projections 13. The annular sleeve, the flat 55 extension and housings are preferably all a single integral casting. The parallel sided recess constituting a chaser housing is open at the inner and outer end, measured radially. The space is also open at the far end of the 60 frame measured longitudinally.

The chasers, designated 20, are plain rectangular blocks having parallel sides, parallel top and bottom edges, a distant end 65 slightly convex but substantially at right angles to the sides and edges, and cutting teeth 21 at the inner edge. Such chasers are adapted to be radially mounted in the housings but they have no coaxing pins or shoulders preventing movement therein. 70 This lends to simplicity in the chaser as it may be made of a simple rectangular block. This is of importance since the necessary hardening of the chaser is liable to cause cracks or weakening strains where any shoulders or notches are formed in them.

To hold the chasers both against outward movement longitudinally of the frame and outward movement radially thereof, I provide a cup-like ring 30 which has an annular 75 flat portion extending over the extreme faces of the chaser housings and also has a cylindrical flange 31 overlapping the outer ends 80 of the housings. Suitable screws 40 pass through the flat portion of the ring 30 and are threaded into the different housing lugs 13, locking the parts rigidly together. This flanged ring therefore by reason of its flat portion limits the outward longitudinal 85 movement of the chasers and by reason of its cylindrical flange, limits the outward radial movement. Preferably, the chasers stand a little higher than the housings, as shown 90 in Fig. 5, so that the ring engages the chasers 95 directly and clamps them rigidly in place, this clamping preventing also any inward radial movement of the chasers.

The description just given of the barrel 100 and the means of holding the chasers therein

applies equally well to the former construction of my assignee above referred to. However, in that construction the members constituting the chaser housings extended continuously in an arcuate direction from one chaser passageway to the next, thus presenting a long arcuate lug, the opposite ends of which make walls of two chaser passageways; and in that construction the cylindrical flange of the cup-like ring extended for the full height of the chasers and beyond them to cover the outer ends of the chaser housings and overlap the periphery of the barrel head beyond the chasers. Thus the chasers were entirely closed in at their outer ends, and arcuate pockets externally closed were left between the different chasers.

In the present invention I make individual lugs for the respective housings leaving wide spaces open to the exterior between each housing and the next and I make the cylindrical flange on the ring so that it extends only part-way along the chaser housings, the extent as shown being approximately two-thirds of the chaser height. I have found that the abutment thus provided for the chasers is amply sufficient to receive the radial thrust thereof and holds them as effectively in place as the former construction. My new construction, however, has the decided advantage in that it provides open spaces between the successive chaser housings for about one-third the height of those housings, this open space leading directly outwardly from the inner or face engaging edge of the chasers.

By reason of the wide radial openings reaching from one chaser housing to the next and extending freely from the pipe region to the exterior, my die stock discharges the chips made by the chasers as fast as formed, instead of allowing them to accumulate within the barrel, as in the former construction.

It should be noted that the widest chip made by the chasers is at the advance edge of the chaser, which is adjacent the radial openings. My die stock, by reason of its openings, allow these wide chips and the adjacent chips to fall out through the openings, keeping the die stock constantly clean.

If any chips should inadvertently be retained by the oil, they may be readily poked out from the front through the openings, by the insertion of a screw driver blade or other tool while the die stock is in any cutting position on the pipe. In contra-distinction to this, the former die stock allowed the chips to accumulate in the pockets between the adjacent chasers. As these chips fell by gravity into the pockets between the housings, the rotating barrel carried them to a position above the pipe where they naturally fell on the pipe and slid toward the cutting edge of the chaser moving upwardly on the left side of the pipe, so that such chips were liable to

pass under the cutting edge and make a ragged cut.

The radial openings in my die stock also provide spaces for the insertion of the point of an oil can to apply oil directly to the cutting teeth of the chasers, and this may be done as the cutting progresses.

The experience of myself and of my assignee with my improved die stock, and the reception which has been immediately accorded it by the trade, demonstrates that by the simple change made I have greatly improved the former die stock and removed the supposedly inherent disadvantage thereof. Incidentally, there is an advantage for the manufacturer of my die stock, in that my abutment ring, by reason of the relatively short cylindrical flange, which may be conveniently made by stamping without unduly drawing the metal.

As heretofore indicated, any suitable means may be employed for rotating the barrel of my die stock. As shown I have employed the annular handle frame 50 carrying a ratchet pawl 52 pressed inwardly by a spring 50, the pawl being faced in either direction, or in an idle position half way between them, by the pulling out of the pawl shank by its head 55 and the turning thereof 90° until a wing 56 on the head is out of alignment with the slot in the frame.

The pawl of the ratchet ring, instead of engaging directly with teeth formed on the barrel, as might be the case, engages, in the embodiment illustrated, a ring 60 rotatably mounted in the handle frame and having teeth on its outer periphery. On its inner periphery this ring has one or more grooves adapted to receive ribs 16 on the sleeve of the chaser barrel. When the barrel is inserted, these ribs 16 pass through notches 58 in the ratchet frame, and then as soon as the frame has moved a short distance with reference to the barrel, the notches are carried out of registration with ribs and then the portion of the frame ring between the notches holds the barrel in place. The barrel can thus only be removed from the rotary frame in one particular relative rotation of the barrel.

I claim:—

1. A chaser carrying frame for a die stock comprising a hollow barrel open at both ends, a set of chaser housings carried by the barrel at one end thereof and each having a radial notch through it, there being clearance openings between successive housings, chasers occupying said notches and a clamping ring overlapping the outer longitudinal ends of the housings and having a cylindrical flange receiving the outward thrust of the chasers and overlapping the clearance openings for part way only of their longitudinal height, whereby said openings are available beyond the end of the ring flange leading outwardly

from a region adjacent to the first cutting edge of the chasers.

2. A driven barrel for a die stock, comprising a sleeve, an outwardly extending head thereon and chaser-lugs arranged in pairs on the longitudinally outer face of the head, there being parallel sided radial passageways to the exterior between the two lugs of each pair, and wider passageways to the exterior 10 between successive pairs, rectangular chasers occupying said parallel sided passageways, and a cup-like ring secured to the housings and having a flange overlapping only the outer longitudinal portions of the chasers and 15 their housings and the space between so as to receive the outward thrust of the chasers and at the same time leave open radial spaces to the exterior along the face of the barrel head and between the chaser housings.
- 20 3. In a die stock, the combination with a driving frame, of a driven barrel adapted to coact therewith, said barrel having a sleeve-like portion adapted to enter the frame, a radially extending annular head on the sleeve-like portion and lugs on the outer face of the head arranged in groups, each group comprising a pair of parallel lugs, such pair leaving between them a space for a chaser, chasers mounted in the lug space mentioned, and there 25 being radially extending flaring spaces to the exterior between successive pairs of lugs, and a clamping ring having an annular flat portion overlapping the longitudinal ends of the chaser lugs and secured to such lugs and having 30 a cylindrical sleeve which extends across the radial ends of the lugs and chasers and forms an abutment limiting their outward movement of the chasers, said flange extending circumferentially across the space between 35 the chaser housings but extending longitudinally for only a portion of the height of such space whereby said space is left open for a material height along the outer face of the barrel head, thus providing 40 a clearance for chips leading directly radially outward from the advance cutting edge of the chasers.

4. In a die stock, the combination of a chaser carrying frame, comprising a rotary 50 hollow barrel open at both ends with radial notches open inward and outwardly radially and at the outer end longitudinally, chasers occupying the notches, there being radial passageways through the wall of the barrel alternating with the chaser notches, and a clamping ring L-shaped in radial cross section and engaging the outer longitudinal edges of the chasers and their rear radial ends, the portion of the ring which engages the rear ends of 55 the chasers terminating short of their inner longitudinal edges to expose a portion of the outer ends of the chasers and to allow access to the radial openings between the chasers.

5. In a die stock, the combination of a 60 hollow barrel open at both ends and having

a driving portion and a cylindrical head larger than the driving portion and connected with it by a lateral annular extension, chasers mounted in radial notches in said head, the inner longitudinal edges of the chasers being substantially flush with said lateral extension, clearance openings formed through the head between adjacent chasers, the inner longitudinal portion of said openings coming to substantially the plane as the inner edges of the chasers, and a clamping ring of L shape 70 is radial cross section having a flat portion overlying and bearing against the outer longitudinal edges of the chasers and having a cylindrical flange overlying and bearing against the outer radial ends of the chasers, said flange terminating short of the longitudinal inner extremity of the radial openings through the enlarged head.

In testimony whereof, I hereunto affix my signature.
